RAILWAY TRAIN OPERATING AND DISPATCHING SYSTEM

Archibald G. Shaver, Chicago, Ill.

Application May 30, 1931, Serial No. 541,131
Renewed July 13, 1937

30 Claims. (Cl. 246—8)

This invention relates to railway train operating and dispatching systems and has special reference to the provision of improved means for communication on and with trains and the operation of track switches and signals for trains to enter passing sidings to meet and pass other trains.

More specifically, the present invention is related to the type of train operating systems described in my applications for Letters Patent filed October 22, 1927 under Serial No. 227,932, September 7, 1928, under Serial No. 304,483, and July 13, 1929 under Serial No. 378,000. In these pending applications, the systems of train operation disclosed provide means for communication between the conductor on the rear and the engineman on the head of trains and between the train dispatcher and either the conductor or the engineman, or both, that information may be had by each and instructions issued with regard to the operation of trains, including trains operating into and out of passing sidings in meeting and passing other trains. Further, in connection with the means for communication there are means for the operation of the switches and signals concerned for trains to enter and leave sidings and pass other trains. In these systems each train operates in a communication zone of its own which always includes an intermediate wayside circuit. The stretch of track over which the trains operate is sectionalized and an intermediate circuit is provided for each section; but as, and during the interval, the train travels from one section to the next, the two intermediate circuits for the adjoining sections are automatically connected together, thus creating a traveling circuit effect. Each intermediate circuit is so arranged as to be in continuous communicative relation with both ends of the train as the train travels through the corresponding section, and each such circuit is also provided with means for communicative connection with the communication means provided for the dispatcher.

For entering and leaving passing sidings means are provided, that the track switch may be operated either from the approaching train or by the dispatcher, and the signals are controlled to protect and authorize the movement of the train over the switch, all in accordance with the understanding had between the conductor, engineman and train dispatcher.

For the system which is the subject matter of the present invention, the systems disclosed in my pending applications, referred to above,

are modified in such manner that the means used for communication between rear end and head end of trains do not normally include the transformer employed for communication between the train and the dispatcher. In this invention, devices are provided for connecting the transformer into the intermediate circuit and the dispatcher's communication circuit when communication between the dispatcher and the train is desired. With this arrangement better results are attained for rear end to head end communication in that the impedance of the intermediate circuits is lowered, and longer intermediate circuits, with consequently longer communicating zones, are possible where desired.

Another object of the invention is the provision of means whereby one device serves to connect two intermediate circuits with the dispatcher's circuit instead of one device for each intermediate circuit for such connection, as is the case in the disclosure of the pending applications referred to.

Another object of the invention is the provision of separate train carried inductors for transmitting and receiving communications on the train.

Provision is made for train operation in a stretch of track containing alternate sections of single and double track where the track switch is always set to enter the double track sections, and trains leaving double track may travel through the switches without stopping.

Still another object of the invention is an arrangement for control of the switch, signal and communication circuits by the dispatcher and the control by the dispatcher of the stopping and starting of the power plants which furnish energy for the operation of the switches, signals and communication control at passing siding locations.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention, and in which:—

Fig. 1 is a diagrammatic view of a portion of a stretch of single and double track showing the communicating system.

Fig. 2 is a diagrammatic view of the arrangement and control of signals at the ends of a section of double track.

Fig. 3 is a diagrammatic view of the inductors.

circuits and communication apparatus carried on the train.

Fig. 4 is a diagrammatic view of the communication system circuits including means for the dispatcher to connect his circuit with a train.

Fig. 5 illustrates means for selectively operating circuit contacts.

Fig. 6 is a diagrammatic view of circuits and means for operating a track switch including a power plant for furnishing electrical energy.

Figures 1, 2, 4 and 6 are fragmentary showings of a stretch of railway track in which T₁ and T₂ are the track rails, BX is a battery for a track circuit, the insulated joints are represented by a short straight line across the line representing the track rails and are generally designated by J, the track switches are designated F followed by a suffix, the manually operated track switch stands are designated by G followed by a number which is the same as that used for the corresponding track switch, track circuit relays are designated E followed by a suffix, signal control relays are designated by C followed by a number for each which is the same as that of the signal to which it refers, selectors are designated by L followed by a suffix, relays co-operating with selectors are designated by K each followed by a number which is the same as that for the selector with which it is associated, and the transformers are designated T followed by a suffix to agree with that for the corresponding selector. The symbols used in the drawings for the signals, relays, relay contacts, batteries, circuits, etc., are those conventionally employed. In these figures various features of the invention are shown segregated to more clearly illustrate the invention.

Fig. 1 illustrates a portion of railroad representative of a district in which there are alternate sections of single and double track. The general arrangement of the communicating system is illustrated in this figure.

CS is generally representative of a section of double track with the switches F₂ and F₃ normally set for trains to enter the double track. BS is generally representative of a section of single track located between two sections of double track. The section AS is a partial view of another section of double track in arrangement like CS. The section DS is a partial view of another section of single track in arrangement like BS. G₁, G₂ and G₃ are switch stands for manually operating the track switches F₁, F₂ and F₃ respectively. In the connection of each of these switch stands to the track switch is a device as H₁, which permits trains to leave sections of the double track without it being necessary for an attendant to set the switch for such movement. In such train operation the train trails through the track switch without causing damage. Signals I to I₂ are block signals with the added function of controlling the passage of trains to and from the sections of double track. The circuits for these signals governing traffic to, from and over the double track section, are illustrated in Figure 2. The circuits for the signals governing traffic on the single track sections may be in accordance with any of the various known practices.

The railroad is divided into sections for track circuit purposes, arranged in accordance with the usual track circuit practice. In Figure 1 the track relays are shown controlling only the contacts operated in connection with the communication system.

DT, DR and DSE are respectively, transmitter,

receiver and selective equipment in the train dispatcher's office. W is a switch arranged for operation by the dispatcher to connect the conductor 113 with either DSE, DR or DT as required. Normally, this switch is in connection with DR, and preferably is so biased by a spring or other suitable means. D₁ and D₂ are way-side conductors along the railroad connected with the dispatcher's telephone and selective equipment, and constitute what is generally referred to as the dispatcher's "telephone line". L₁, L₂, L₃, etc., are selectors adapted to be operated by the dispatcher in connection with his selective equipment DSE to control relays K₁, K₂, K₃, etc. These relays K close circuits in either of two positions. Such relays are generally known as "off and on" relays and the actual contact operating members may take the form of the cam and ratchet arrangement shown in Figs. 5 and 6. The selectors L₁, L₂, and L₃ respectively control contacts 42, 46 and 50. With any one of these contacts closed, the corresponding relay K is energized to shift its contacts, which remain in the position to which shifted until the selector is again energized to close its contact 25 when the relay K shifts its contacts to the other illustrated position. H is a relay controlled by contacts of the track circuit relays E₅, E₆, E₇ and E₈. The function of this relay under normal conditions is to connect the intermediate 30 circuit for the double track section CS to the dispatcher's telephone line D₁ and D₂ for communication with the dispatcher so that the train attendants may initiate the conversation.

The intermediate circuits for sections BS and CS are typical of the single and double track section arrangement. There is only a partial showing of the intermediate circuits for sections AS and DS. The intermediate circuit for section AS when shown complete would be like that illustrated for section CS and the intermediate circuit for section DS if shown complete would be like that illustrated for section BS.

Shown within the section BS is a train No. 6 with a rear end car or caboose CA and a locomotive LO at the head end. Shown on track M₂ of the double track section CS is a train No. 5 also with a car or caboose CA at the rear end and a locomotive LO at the head end. These two trains illustrate a condition where train No. 6 will proceed along the single track main line into track M₁ of the double track section passing train No. 5 while the latter is on the track M₂. As the trains leave the section they will pass over the switches, as F₂ and F₃, without stopping, as heretofore explained.

Z illustrates a sub-section of any arbitrary length.

The intermediate circuit for section BS normally comprises conductor 18, contact 19, conductor 20, contact 21 and back contact 22. The conductors 18 and 20 are transposed at intervals to form an equal number of loops. Either conductor 18 or 20 is always so located on the railroad, preferably in the center of the track on the ties, as to be in inductive relationship with the inductors carried on the train.

The intermediate circuit for double track section CS normally comprises conductor 23, contact 24, conductor 25, contact 26, conductors 27 and 30, and contact 29 closed. It will be noted that as illustrated there is a conductor for each track. While but one transposition is shown, others, to make an equal number of loops, may be provided if necessary. Since train No. 5 shunts 75

- the circuit for relay E8, this latter is de-energized, opening its front contact A60, which results in relay H being de-energized to open its front contact 29 and close its back contact 38.
- 5 The intermediate circuit for section CS is now closed through front contact 28 and coil S of transformer T3. Also, primary P of transformer T3 is connected to the dispatcher's telephone line conductors D1 and D2 by conductor 41, contact 10 40, conductor 39, back contact 38 closed, transformer primary P and conductor 37.

The selector L1 is connected across the conductors D1 and D2 by the conductors 67 and 33. Selector L2 is connected across the conductors D1 15 and D2 by the conductors 68 and 36. The selector L3 is connected to the conductors D1 and D2 by the conductors 37 and 41.

The circuit for relay K1 comprises battery B1, conductor 43, contact 42 normally open, conductor 20 45, coil of relay K1 and conductor 44. The circuit for relay K2 comprises battery B2, conductor 47, contact 46 normally open, conductor 49, coil of relay K2 and conductor 48. The circuit for relay K3 normally comprises battery B3, conductor 53, contact 50 normally open, conductor 51, coil of relay K3 and conductor 52.

That much of the partial intermediate circuit for section AS, as is shown, comprises conductor 17, back contact 16, conductor 15, contact 14 and 30 conductor 13.

That much which is shown of the partial intermediate circuit for section DS comprises conductor 63, contact 64 and conductor 65.

The circuit for relay H comprises battery BY, 35 contact 55, conductor 56, contacts 57 and 58, conductor 59, coil of relay H, conductor 60, contact A60 normally closed, and conductors 61 and 62. It will be noted by reference to Figure 6 that battery SY and generator U1 are illustrated as a 40 source of energy for relay H and its circuit, as an alternative for battery BY.

Conductors 111 and 113 connect DT, DR and DSE to conductors D1 and D2, depending upon the position of switch W.

45 Figure 2 is typical of the signal arrangement for a section of double track as CS. Trains move right-handedly on the tracks. Signals 6 and 9 govern trains entering the double track in accordance with the established direction of traffic. Signals 8 and 11 govern traffic over the track switches F2 and F3 into the double track in the direction against the regular current of traffic. Signals 5 and 10 govern train movements from double track to single track, in accordance with 50 the established direction of traffic. Signals 7 and 12 govern trains from double track to single track against the established current of traffic.

60 Contacts 72 and 79 are connected for operation when switch F2 is opened and closed, contact 79 being closed with switch F2 in the normal or closed position and 72 being closed with switch F2 in the open or reverse position. Contacts 97 and 104 are connected for operation when switch F3 is opened and closed, contact 97 being closed 65 with switch F3 in the normal or closed position and contact 104 being closed with switch F3 in the open or reverse position.

65 Relays C5 to C12 inclusive are the relays for controlling the correspondingly numbered signals; that is, control relay C5 operates to control signal 5, etc. CM1 and CM2 are commutator devices or contacts selectively controlled by the dispatcher, in some such manner as illustrated in Figure 5 and as hereinafter referred to. The 70 75 shaded section of each of these commutator con-

tacts illustrates the closed position of the commutator or contact in its respective circuit, for example, contacts O1 and O3 are normally in the position closing their respective circuits. Contact O2 closes its circuit only when operated to 5 its fourth position. Contact O3 also closes its circuit in position three. Contact O4 closes its circuit in position three. The circuits connected with the commutator devices CM2 are generally closed as explained for commutator device CM1 10 and as recited in Figure 2.

The circuit for control relay C5 comprises common conductor C, coil of relay C5, conductor 83, normally closed commutator contact O1, conductor 84, contacts 85 and 86, conductor 119 and 15 through the other circuit controlling contacts of the block to battery and common conductor C.

The circuit for control relay C6 comprises common conductor C, coil of relay C6, conductor 76, relay contact 77, switch operated contact 79 20 closed, conductor 88, normally closed contact of commutator O8, conductor 84, contact 82 closed, conductor 117 and through the other circuit controlling contacts of the block, if any, to battery and common conductor C. The circuit for control relay C7 comprises common conductor C, conductor 81, contact O2 normally open and conductor 88 to conductor 84, and then proceeds in common with the circuit for control relay C5 already explained. The circuit for control relay C8 comprises common conductor C, coil of relay C8, conductor 69, contact 70, conductor 71, normally open switch controlled contact 72, conductor 73, normally open contact 04, conductor 74, contact 75, conductor 118 and 35 through other circuit controlling contacts of the block, if any, to battery and common conductor C. The circuit for control relay C9 comprises common conductor C, coil of relay C9, conductor 96, normally closed switch controlled contact 97, 40 conductor 98, contact 99, conductor 100, normally closed contact O7, conductor 101, contact 102, conductor 116 and through other circuit controlling contacts of the block, if any, to battery and common conductor C. The circuit for control 45 relay C10 comprises common conductor C, coil of relay C10, conductor 89, normally closed commutator contact O6, conductors 90 and 92, relay contacts 93 and 94, conductor 95 and through other circuit controlling contacts of the block, if any, 50 to battery and common conductor C. The circuit for control relay C11 comprises common conductor C, coil of relay C11, conductor 103, normally open track switch controlled contact 104, conductor 105, contact 106, conductor 107, normally 55 open contact O8, conductor 108, contact 109, conductor 110 and through other circuit controlling contacts of the block, if any, to battery and common conductor C. The circuit for relay C12 60 comprises common conductor C, coil of relay C12, contact O5 normally open, conductor 92 and thence common with the circuit for control relay C10, already explained, to battery and common conductor C.

The signals illustrated in the various figures, 65 including those in Figure 2, may be of either the two or three position types and they may be semaphores or light signals. For convenience, the semaphore type is illustrated. The corresponding control relays, as C5 to C12, may be of 70 the ordinary electro-magnet type for two position signaling or of the polarized type for three position signaling. Two position and three position signaling is well known in the art as are also polarized relays. I have not illustrated means 75

for controlling the circuits for three position signalling since that is not especially pertinent to the invention.

Figure 3 is a diagrammatic illustration of the circuits and equipment for locomotives and cabooses. Two inductors RN and TN, each comprising a coil on an iron core, respectively for receiver RE and transmitter TR are mounted on locomotives and cabooses so as to be in inductive relationship with the intermediate circuits heretofore explained. The circuit for transmitter TR comprises conductor 155, normally open circuit controlling contact 160, conductor 158, coil 157 of the inductor TN, and conductor 156. The circuit for the receiver RE comprises conductor 151, normally closed circuit controlling contact 159, conductor 154, coil 153 of inductor RN and conductor 152. The switch SH is arranged to control both the transmitter and receiver circuit, such that only one can be closed at a time. Under certain conditions I may dispense with the use of this switch, in which case the inductors RN and TN are so mounted and the circuits so protected that there may be simultaneous transmission and reception of communication signals without the necessity for opening the circuit for receiving when it is desired to transmit. With such an arrangement, transmission and reception of communicating signals, voice communication for instance, may be carried on in a manner similar to that for the usual public telephone systems. 23 illustrates a preferred position of a conductor of the intermediate circuit with reference to inductors RN and TN, as, for example, conductor 23 of intermediate circuit CS which has a similar relationship with the inductors on the locomotive LO and caboose CA of train No. 5.

The transmitter TR and the receiver RE are assumed to be suitably arranged for either audio or radio transmission of communication signals, depending upon which system is used. In general, it is desirable to so design these units that the transmitter output will be relatively large and the receiver amplification, where required, will be relatively small. This is particularly true where communication is carried on with audio frequency, and there is probability of foreign inductive disturbances affecting the reception. In the use of radio frequencies in this communicating system, I may alternatively, employ the loop type of inductors rather than those with iron cores as illustrated.

Figure 4 is illustrative of the wayside communicating system applied to a stretch of track with special reference to means for connecting the dispatcher's selective and telephone circuit, conductors D1 and D2, with two intermediate circuits at the same time. In the case of a double track railroad, the arrangement as disclosed would either be duplicated, or, instead of having conductors on each of the tracks interconnected, the track conductors would be connected with separate conductors on a pole line. The intermediate circuits may each be completely on the two tracks, with one conductor on one track and another conductor on the other track, the two connected together at the ends of the section making a complete loop. In the case of this latter arrangement, track circuit sections in the second track, not shown here-with, would control the respective track relays E10, E11, E12, etc., of the track shown such that, as the train passes over the second track, the various intermediate circuits would be operated as will now be described for the stretch of track 75 shown.

In the figure are two complete intermediate circuits, one for section FS and the other for section GS. Only partial intermediate circuits are shown for the partial sections ES and HS; but if these circuits were shown complete, that for ES would be like GS and that for HS like FS. For the section FS, the intermediate circuit comprises conductor 123, back contact 124, conductor 125, front contact 126, conductor 127 and front contact 128. For the section GS the intermediate circuit comprises conductor 129, front contact 130, conductor 131, back contact 132, conductor 133 and front contact 134.

With relay E11 de-energized the contacts 134, 126 and 139 are made on their back points so that the intermediate circuits for sections FS and GS are connected together into one enlarged intermediate circuit comprising conductor 123, back contact 124, conductor 125, back contact 126, conductor 129, front contact 130, conductor 131, back contact 132, conductor 133, back contact 134, conductor 127 and front contact 128 connecting to conductor 123.

It will be noted that normally each illustrated section has two equal loops because of one transposition in each section. With the relay E11 de-energized another transposition is effected, making in the enlarged intermediate circuit, four equal loops.

The circuit for relay K4 comprises contact 148, 30 conductor 149, battery B4, conductor 146, coil of relay K4, and conductor 147. With contact 148 closed, which may be but momentarily, relay K4 is energized, shifting its contacts 124, 132 and 144 to their front points, connecting transformer 35 secondary S2 through front contact 124 into the intermediate circuit for section FS, connecting secondary S1 through front contact 132 into the intermediate circuit for section GS, and connecting primary P through front contact 144 across 40 the conductors D1 and D2. With the train occupying the track circuit for relay E11, this relay is de-energized, as heretofore explained. Contact 139 being closed, secondary coil S1 is now shunted from the intermediate circuit by reason of the 45 circuit being closed through conductor 141, back contact 139 and conductor 142. It will, therefore, be noted that with the train in the section of relay E11, not only are the two intermediate 50 circuits for sections FS and GS joined together as one circuit, but with the dispatcher having operated his selector L4 to place his communicating set in communication with the train, but one secondary coil S2 remains connected in the 55 enlarged intermediate circuit so long as it remains as such. With relay E11 normal, the separate intermediate circuits for section FS and GS are again effective. When the dispatcher again operates selector L4, the relay K4 shifts its contacts 60 back to normal and the transformer secondaries S1 and S2 and primary P again resume normal status.

The functions of the relays E10 and E12 are simply that of connecting the adjacent intermediate circuits, that is, ES and FS, together while the train is in the circuit of E10 and GS and HS together while the train is in the circuit of E12. Assuming relays E10, E11 and E12 each to represent a track circuit location, the arrangement as 70 shown at the location for E11, is repeated for every other track circuit location. In this way the dispatcher by operating one selector, like L4, placed at every other location, is enabled to connect his selective and telephone circuit, conduct- 75

tors D1 and D2, with every intermediate circuit for the track stretch.

In Figure 5 is shown a method for operating a plurality of commutator contacts from one selector; for example, the commutator combinations CM4 and CM5. L5 is a selector operated from the dispatcher's office over conductors D1 and D2 by the selective equipment DSE. When so operated, contact 232 is closed, which may be but momentarily. 236 is a gear or toothed wheel. When contact 232 is closed, relay K5 is energized from battery B5 through conductor 234, coil K5, conductor 233, contact 232 and conductor 231. This causes armature 235 to be raised, such that the latch connected with it causes gear 236 to rotate counter-clockwise each time K5 is energized. Commutators O9, O10, and O11, are on the same shaft and movable with gear 236. The circuits connected with these commutator contacts are made and broken as desired. As illustrated in Fig. 5, four positions are obtainable. While I have shown this particular detailed arrangement for operating commutator contacts, there are other equally efficient methods of accomplishing the same purpose. Therefore, I do not want to be confined to the use of the particular arrangement shown.

In Figure 6 is illustrated means for the dispatcher to operate the track switch F2, and to control the power plant for furnishing the energy for operating the switch F2 and for operating the signals which govern traffic over the switch F2. HTS is a hand throw stand for manually operating the track switch F2. SM is a mechanism for operating the switch F2, and M is the motor which drives the mechanism.

6 is a signal governing trains over the switch along the main line. 8 is a signal governing trains from the main line into the siding. 5 is a signal adapted to govern trains from the siding to the main line. 7 is a signal arranged to govern trains along the main line trailing over the switch.

The control relays C5 to C8 control respectively signals 5 to 8. The circuit for relay C6 comprises common conductor CW, conductor 151, front contact 152, conductor 153, coil of relay C6, conductor 158, normally closed commutator contact O10, contact 159 closed when switch F2 is in normal position, contact 160 closed when switch F2 is locked, and thence through other controlling contacts of the block, if any, to battery and common conductor CW. The circuit for control relay C8 comprises common conductor CW, conductor 151, contact 152, conductor 153, coil of relay C8, conductor 154, contact 155, closed only when switch F2 is open, contact 156 closed when switch F2 is locked in the reverse position, conductors 157 and 224, battery SY to common conductor CW. The circuit for relay C5 comprises common conductor CW, conductor 176, coil of relay C5, conductor 180, contact 191 closed when switch F2 is locked in the reverse position, contact 190 closed only when switch F2 is open, conductor 192, contact 193, contact 194 and conductor 195 through other circuit controlling contacts in the block, if any, to battery and to common conductor CW. The circuit for control relay C7 comprises common conductor CW, conductors 229 and 196, coil of relay C7, conductor 197, contact 198 closed when the switch F2 is closed and locked, contact 199 closed only when the switch F2 is closed, commutator contact O9 normally closed, conductors 200 and 192 and thence in common with the circuit above explained for control relay C5.

The power plant for this switch, signal and

relay location comprises gasoline engine GE directly connected to generators U1 and U2. ST is the starting motor, which, when energized, connects itself through a clutch with engine GE to start same operating. Battery SY furnishes energy for the starting motor ST and for the various relay and signal circuits. SCC is a circuit controller fastened to the common shaft of the gasoline engine GE and the generators U1 and U2. The contact 226 is normally closed, but opens when the speed of the gasoline engine GE reaches a point where it is self-operating. Thus, when this point is reached, the starting motor ST is de-energized and disconnected from gasoline engine GE. The generator U1 furnishes energy for charging the battery SY and for operating the various relays and signals as indicated and explained. RR is an electrolytic cell, or other device, to prevent a reversal of current; that is, a flow of current from battery SY to generator U1. In case, for some reason, the voltage of the current delivered from U1 fails below that for the battery SY. CM4 and CM5 are assemblages of commutator contacts each operated selectively by the dispatcher. SR is a relay for controlling the operation of the motor M.

When contact 205 is closed, signal 6 becomes operative to authorize an approaching train to proceed over the switch along the main line. Its circuit comprises common conductor CW, conductor 202, mechanism of signal 6, contact 205, conductors 201 and 224, and battery SY connected to common conductor CW. When contact 204 becomes closed by reason of relay C8 being energized, the circuit just described is closed between conductors 201 and 202 and signal 8 becomes operative to authorize a train to proceed into the siding. When relay C7 is energized, closing contact 207, signal 7 becomes operative to authorize a train to proceed over the switch along the main line, energy being furnished through contact 207 from conductors 201 and 202. When contact 206 is closed, signal 5 becomes operative for a train to move from siding to main line due to the circuit being closed between battery leads, conductors 201 and 202.

The circuit for the starting motor ST comprises common conductor CW, battery SY, conductor 224, motor ST, conductor 225, contact 226, conductor 227, commutator contact O13 closed in position 2, and conductor 228, connected to common conductor CW.

EP is a battery or magneto in the ignition circuit for the gasoline engine GE. This ignition circuit comprises battery EP, conductor 215, ignition contacts in engine GE, conductors 216 and 217, commutator contact O12, closed in position 2, and ignition energy EP. The circuit for relay SR comprises common conductor CW, conductor 223, commutator contact O11 closed in position 3, conductor 222, coil of relay SR, conductor 221 and battery SY connected to common conductor CW. The circuit for motor M to open the switch F2 comprises generator U2, conductor 214, contact 213, conductor 212, contact 211 closed on its front point, conductor 210, motor M and conductor 208 connecting to generator U2. For closing the switch F2, the circuit is as above described, excepting contact 211 is closed on its back point, and conductor 209 connecting to motor M completes the circuit.

Contained in the mechanism for motor M is a circuit controlling device so arranged that when the motor is operated to open the switch, the operation of locking the switch in the open posi-

tion opens the circuit normally closed over conductor 210 and closes a circuit over conductor 209. When the switch has been operated to the closed position and is being locked, the circuit controlling device, above referred to, again operates, opening the circuit closed over conductor 209 and reclosing the circuit over conductor 210. This is a well known practice in electric power switch operation incorporated in the systems of 10 various signal companies.

Also getting energy from battery SY and generator U1, through the conductor 237, contact 238 and conductors 201 and 224, and returning through common conductor CW, is the control 15 relay (not shown) for the distant signal (also not shown) for signal 6. The relay H of Fig. 1 is also shown by the partial circuit, contacts 58 and 57, conductor 56, contact 55, conductors 201 and 224, battery SY and common conductor CW as getting its energy from the power plant of Fig. 6 in the case that the track switch F2 of Fig. 1 is power operated. The conductor CW under such circumstances compares with the conductor 20 62 of Fig. 1.

25 The hand throw switch HTS has two levers. In operation, one lever disconnects the power mechanism SM and the other then operates the switch F2.

Operation

30 Referring to Figure 1, assume trains No. 6 and No. 5 have to pass each other. Dispatcher instructs train No. 5 as it approaches station Y that train No. 6 will pass it while it is in the double track section CS. He also instructs train 35 No. 6 as it approaches station Y that train No. 5 will be passed in the section CS. As a precaution that neither train will leave the double track section till both trains have arrived within the 40 section, the dispatcher causes signals 5 and 10 to indicate "stop". After having received the dispatcher's instructions, the conductor in the caboose and the engineman in the locomotive cab of each train confer with regard to the dispatcher's instructions, and arrangement between 45 themselves is made as to such details for operation of their respective trains as are necessary. Upon the arrival of each train within the section CS, each conductor will report the arrival of his 50 train to the dispatcher. He will also engage in communication with the engineman to make certain of the identity of the other train as it is passed. The dispatcher will then release each 55 of the signals 5 and 10 that each train may proceed. If the two trains have arrived in the section CS before either has stopped for its respective outbound signal (signal 5 for train No. 5 and signal 10 for train No. 6), the dispatcher will 60 release the signals to "clear" so that each train may proceed without having to stop. As each train leaves the double track section CS, for example when the train No. 5 is in the track circuit of relay E5 and train No. 6 is in the track circuit for relay E8, the conductor of the train advises the dispatcher of that fact, the location of the train, and any other information desirable for the dispatcher to have in connection with the proper 65 operation of trains.

As heretofore stated, Fig. 2 is typically illustrative of the normal arrangement of signals, circuits and operative devices for signals for the double track sections in the stretch of track referred to in Fig. 1, and for this purpose is arranged as applying to the section CS.

75 In Fig. 1, signal 5 is at "stop" because of train

No. 6 within its block and signal 10 is at "stop" because its block is occupied by train No. 5. These same signals may also be at stop due to the dispatcher having opened the circuits at contacts O1 and O6 by the operation of selector controlled commutators CM1 and CM2 respectively. While these signals are at "stop" with trains in their blocks, the dispatcher would necessarily have to place these signals in a condition to indicate "stop" to cover such a situation as where 10 train No. 5 would arrive at signal 5 to leave the double track section CS before train No. 6 had entered the block of signal 5.

Considering now the procedure in the passing of the two trains No. 5 and No. 6 as referred to 15 above, the dispatcher communicates with train No. 5 and gives it the instructions while it is within the section DS, which is but partly shown. It has been heretofore stated that the communication arrangement for section DS is similar to 20 that for section BS, and therefore, the procedure in instructing train No. 5 and receiving a reply may be considered the same as that which follows for train No. 6.

In communicating with train No. 6 in the section 25 BS, the dispatcher first operates switch W and causes the selective equipment DSE to operate to send out the code of current impulses to which selector L2 is responsive, these impulses following the circuit of conductors 113, 111, D1, 30 D2, 68 and 36. When selector L2 responds contact 46 closes causing relay K2 to close its contacts 22 and 35 on their front points. This operation connects primary P of transformer T2 to conductors D1 and D2 at contact 35 and secondary 35 S into the intermediate circuit for section BS at contact 22. The dispatcher next closes switch W on conductor 112 to connect the transmitter DT to conductors D1 and D2. He now transmits his communication signals (assume they are voice 40 signals) in the form of electric impulses to the circuit including the conductors D1 and D2 and coil P. These signal impulses are induced from coil P into the intermediate circuit for section BS, through the secondary S of transformer T2 45 and conductors 18 and 20. Since the receiving sets RC and RL of the caboose and locomotive respectively, each of which includes the inductor RN in circuit with receiver RE, are normally in inductive relation with conductors 20 and 18, the 50 signal impulses are picked up by the respective inductors RN and carried to the receivers RE where they are transformed into the communicating signals which the dispatcher transmitted. As soon as the transmission of the instructions is 55 complete, the dispatcher closes switch W (usually it will be arranged to automatically so operate) to place the receiver DR in circuit with conductors D1 and D2. Assume the conductor and engineman of train No. 6, one following the other, reply 60 to the dispatcher, acknowledging the instructions. Each does this by operating the switch SH of Fig. 3 so that the circuit for the transmitter TR is closed and the circuit for the receiver RE opened. Each will repeat into his transmitter, again as 65 suming voice communication, that which he wishes the dispatcher to know. These signals in the form of communicating current impulses pass through the coil 157 of the inductor TN, thus setting up a magnetic field which induces corresponding current impulses into the intermediate 70 circuit including conductors 18 and 20 and secondary S of transformer T2. Within transformer T2 these signal impulses are induced into the primary P, including the conductors D1 and D2 75

and the receiver DR where they are transformed into the communicating signals (speech) transmitted by the conductor and engineman of train No. 6. When the conversation is finished, the 5 dispatcher again operates switch W to close the circuit for the selective equipment DSE to send a code of impulses to selector L2 which responds, closing contact 46. Thus relay K2 is energized to again shift its contacts to the normal position, 10 that is, closing contact 22 on its back point and opening contact 35. This operation disconnects the dispatcher's circuit from intermediate circuit of section BS.

Should the dispatcher have found it more convenient to do so, he might have operated the selector L2 for the section BS and the appropriate selector (not shown) for the section DS connecting the respective transformers in the circuit containing conductors D1 and D2, so that the intermediate circuits for sections BS and DS would be connected to the conductors D1 and D2 at the same time. Then he could have simultaneously given his instructions to trains No. 5 and No. 6. The replies from each train, acknowledging the 25 instructions, could then come in one following the other in the order in which he would indicate.

The dispatcher now causes the signals 5 and 10 to indicate "stop." In Fig. 5 it was indicated how commutators such as CM1 and CM2 are 30 operated. The dispatcher, first sends out a series of the appropriate code of impulses to cause the selector for CM2 to operate the latter to position 3, closing contact O1 and opening contact O6, which places the circuits in condition for signal 35 9 to indicate "proceed" and signal 10 to indicate "stop." He again sends out a series of appropriate impulses to operate the selector corresponding to commutator CM1, operating this commutator to the position 3, to place the circuits 40 through contacts O1 and O3 for signals 5 and 6 in condition for signal 5 to indicate "stop" and signal 6 to indicate "proceed." Following communication from and with the dispatcher, the conductor and engineman of each train communicate with each other with reference to the 45 instructions from the dispatcher and other matters pertaining to the operation of the train in passing other trains, including identification of the trains passed.

50 The train No. 5 being assumed still in the section DS, the procedure in the communication between the conductor and engineman will be similar to that which is now about to be described for train No. 6. The conductor of train No. 6 initiates the conversation by operating switch SH of his set RC-TC to open the receiver circuit and close the transmitting circuit. He then transmits communication current impulses which energize the inductor TN to induce corresponding 55 impulses into the intermediate circuit which includes conductor 20. As this intermediate circuit is closed, including also conductor 18 which is transposed with conductor 20, the electrical impulses corresponding to the communication 60 signals are carried through this closed circuit as heretofore described. The receiving set RL on the locomotive being in communicative relationship with conductor 20, the inductor RN is influenced to transmit the corresponding communicating 65 current impulses to the receiver RE where they are transformed into the communicating signals transmitted. These signals may be either by code or by voice. The conductor's switch SH is now restored to normal condition. The engineman, in replying to the conductor, operates 70

switch SH of his transmitting and receiving sets TL and RL respectively, opening the circuit of the receiver RE and closing the circuit of the transmitter TR. He then transmits communicating impulses into the inductor TN on the locomotive. This influences the intermediate circuit, of which conductors 18 and 20 are a part, so that electric impulses corresponding to the transmitted signals pass through this intermediate circuit influencing the inductor RN of the 10 receiving set RC such that the electrical impulses are carried in the circuit of the inductor RN to the receiver RE where they are transformed into communicating signals which were transmitted from the locomotive. During the time this communicating is taking place the train may have entered the track circuit for relay E4 in which case the intermediate circuits for sections BS and CS are combined and the communicating impulses between the head end and rear end will 20 then pass through this enlarged intermediate circuit, which has been heretofore described.

Normally, the relay K3 is in the position shown. With train No. 5 operating on track M2 of section CS in the position shown, relay E8 is de-energized, opening the circuit of relay H. With front contact 29 open, the intermediate circuit for the section CS is connected through the secondary S of transformer T3. With the back contact 38 closed, the primary P of transformer T3 30 is connected across the dispatcher's line, conductors D1 and D2. The conductor of train No. 5 may now talk to the dispatcher. He operates switch SH of his receiving and transmitting set RC-TC, opening the circuit for the receiver RE 35 and closing the circuit for the transmitter TR. He transmits the communicating impulses announcing his arrival on track M2 into the circuit of inductor TN, energizing same with electrical impulses corresponding to the communicating impulses transmitted. These electrical impulses influence the conductor 23 of the intermediate circuit for section CS, thus causing these impulses to pass through the secondary S 40 of transformer T3 where they are induced as 45 corresponding current impulses in the primary P of the transformer T3 and through conductors D1 and D2 to the dispatcher's receiver DR, which is normally connected with the conductors D1 and D2. In the dispatcher's receiver DR these 50 current impulses are transformed into the communicating impulses transmitted by the conductor from the train. If the dispatcher wishes to reply or give any information to train No. 5 he shifts his switch W to conductor 112, thus connecting his transmitter DT with the conductors D1 and D2 and proceeds to transmit his reply as 55 communicating impulses into the circuit including conductors D1 and D2 and the primary of transformer T3. These impulses are induced 60 from the primary to the secondary of the transformer T3 and thus into the intermediate circuit for section CS. Since the receiving sets RL and RC have again been placed in normal communicative relationship with the intermediate circuit, including the conductor 23, the electrical communicating impulses influence the inductors RN of these sets on both ends of the train such 65 that corresponding impulses are carried to the receivers RE and transformed into the communicating signals transmitted by the dispatcher.

When train No. 6 arrives in the circuit for track relay E5, the latter is de-energized, opening contact 58, which would de-energize relay H were it not already de-energized due to train 75

No. 5 within one of the track circuits controlling relay H. The procedure by the conductor of No. 6 in announcing the arrival of his train within the section CS and by the dispatcher in making a reply, if any, is the same as that already explained for train No. 5.

Should the dispatcher find the exchange of communications between conductors and engineers bothersome, he may disconnect the intermediate circuit for section CS from the conductor D1 and D2 by operating selector L3 to cause relay K3 to shift contact 28 to its back point and open contact 40. Such operation leaves the intermediate circuit for section CS in condition for inter-train and intra-train communication.

As trains No. 5 and No. 6 are now both in the section CS and their train carried communication sets are in communicative relation with each other through the intermediate circuit for CS, the conductors of each train, or the engineman of each train, or all of them, may communicate with each other in exactly the same manner as heretofore explained for conductor and engineman on the same train, and thus each may establish for a certainty the identity of the train being passed and exchange such other information as seems desirable.

Since the dispatcher is advised that both trains are now in the double track stretch CS, he will close the switch W on conductor 115 and operate the selective equipment DSE to send out the appropriate code to operate the selector controlling commutator CM1, stepping the commutator contacts around to the normal position which is position 1. This closes the circuit for control relay C5 through contact O1 so that signal 5 may indicate "proceed" providing its block is clear, for train No. 5 to enter the single track stretch BS and continue on its way. The dispatcher also sends out the appropriate code for the selector controlling commutator CM2 stepping same around to its normal position or position 1. This completes the circuit for control relay C10 through contact O6 so that signal 10 may indicate "proceed", providing its block is clear, so that train No. 6 may pass from the double track section CS into the single track section DS.

As train No. 5 is about to leave track M2 to enter the single track section BS, the conductor of this train operates his switch SH opening the receiver circuit of his receiving set RC and closing the transmitting circuit of the transmitting set TC. Relay K3 having been restored to normal, he announces in the transmitter TR to the dispatcher that the train is leaving the double track section CS. This causes current impulses, corresponding to the signals transmitted, in the circuit of inductor TN on the caboose, thus influencing the intermediate circuit for section CS of which conductors 25 and 23 and transformer T3 are a part. These current impulses are induced from the secondary S into primary P and thus into the dispatcher's circuit containing conductors D1 and D2 and carried to the dispatcher's receiver DR, where they are transformed into the transmitted communicating signals.

As train No. 6 leaves the section CS, its conductor also announces the departure of that train into the single track section DS and the procedure in making the announcement is similar to that already described for train No. 5.

When train No. 5 passes into the circuit for track relay E4, the intermediate circuits for sections CS and BS are combined into one enlarged intermediate circuit. During this time and until

the train leaves the circuit for track relay E5, communication may be initiated with the dispatcher. Similarly, this is true for train No. 6. As it enters the circuit of track relay E9, the intermediate circuits for sections CS and DS are combined. During the time the train is in this track circuit, and until it clears the track circuit of relay E8, communication with the dispatcher may be initiated on the train No. 6. In cases where such may be desirable, the engineman, instead of the conductor, may report to the dispatcher that the train is leaving the section CS and he may initiate the conversation similarly as referred to above for the conductor.

While one of the trains referred to is in the track circuit for relay E4 and the other train is in the circuit for track relay E9, there may be communication between their train carried communication stations via the enlarged intermediate circuit for the sections BS, CS and DS. Relays E4 and E9 being deenergized, the intermediate circuit for the section CS is connected at one end with the intermediate circuit for section BS and at the other end with the intermediate circuit for section DS.

In Fig. 4 is shown a somewhat different arrangement for the dispatcher to connect his station with the intermediate circuits for communication with a train. If the dispatcher wishes to have communication with a train in either section FS or GS, or trains in each of these sections, he will move his switch W (see Fig. 1) from the normal position to connect with conductor 115, and send out a code of impulses to which selector L4 will respond. When contact 148 is closed, relay K4 is energized to shift its contacts 124, 132 and 144 to their front points, the latter connecting primary P to conductors D1 and D2. The closing of front contact 132 connects secondary S1 of transformer T4 into the intermediate circuit for section GS. The closing of front contact 124 connects secondary S2 into the intermediate circuit for section FS. The dispatcher may then initiate and carry on communication with trains in either or both of these sections similarly as heretofore explained. Should he be communicating with the train in section FS and it should proceed into the circuit for track relay E11, then the intermediate circuits for sections FS and GS are transposedly connected together into one enlarged intermediate circuit. During this time, back contact 139 is closed in parallel with back contact 134 and front contact 132 so that transformer secondary S1 is shunted. This leaves but one transformer secondary in the circuit and reduces the impedance of the enlarged intermediate circuit in the case of rear end to head end conversation during this time. The use of such an arrangement as indicated in Fig. 4 decreases the number of selectors necessary to be operated in the dispatcher's selective system over the conductors D1 and D2. It also makes possible the operation of the system over a long track stretch, where the selector system is such that only a given number of selectors can be operated on any one circuit.

Assuming a train in section GS is passing through the track circuit of relay E12 to the section HS, then the intermediate circuit for section HS, which is only partially shown but which is similar to that for section FS, will be transposedly connected with the circuit for section GS making one enlarged intermediate circuit. During this interval communication between the dis- 75

patcher and the train may still be carried on through the transformer secondary S1.

In Fig. 6 is illustrated an arrangement of circuits and apparatus at a switch where there is only single track in the stretch, instead of alternate sections of single and double track. Passing sidings are assumed to be provided at intervals that trains may pass each other. It is also desirable for the dispatcher to control the operation of the track switch for trains to leave and enter sidings. It is further desirable that the dispatcher control the operation of the power plant for furnishing electrical energy to the various relays, signals and switch mechanism motor.

In such a lay-out, the arrangement of the communication circuits will be the same as that already explained for Fig. 1. The commutator CM4 controls the operation of the main line signals at each passing track end and the circuit for operating the switch mechanism for the motor M. The commutator CM5 controls the operation of the power plant. Both commutators CM4 and CM5 are operated in the manner shown in Fig. 5. Let it be assumed that this method of switch and signal control is applied to the switches in Fig. 1, and that the sections shown as double track in that figure are in reality sections of single track with a passing siding. Normally, trains keep to the main track unless there is necessity for them to enter the siding. Assume there are two trains, as No. 5 and No. 6, approaching a passing track location. The dispatcher communicates with both as heretofore described in connection with Figure 1.

The arrangement shown in Fig. 6 will be in use at each end of the siding so that switches F2 and F3 will both be controlled by the dispatcher. After communicating with the trains and instructing them that they are to pass at the station Y, train No. 6 to enter the passing siding and No. 5 to keep to the main line, and getting a reply from them that the instructions are understood, the dispatcher closes the switch W and operates the selective equipment DSE to send the appropriate code of impulses to the selector operating commutator CM4, placing this commutator in the position 3. This opens the circuits at contacts O10 and O9 for control relays C6 and C7 causing both signals 6 and 7 to give the "stop" indication. With the closure of contact O11 relay SR is energized and its contact 211 is caused to be made on its front point. This places the motor M in condition to operate to open the track switch F2 so that train No. 6 may enter the siding. The dispatcher again operates his selective equipment DSE sending out an appropriate code of impulses to operate the selector controlling commutator CM5 operating this commutator to the position 2, which closes the ignition circuit for the gasoline engine GE through contact O12 and the circuit for the starting motor ST through the contact O13. The starting motor then operates from battery SY connecting itself through a suitable clutch with gasoline engine GE to turn the gasoline engine over to start same. As soon as gasoline engine GE has reached the speed at which it is operative from its own power, circuit controller SCC opens, stopping motor ST and disconnecting it from gasoline engine GE.

Gasoline engine GE is directly connected with generators U1 and U2, each of which delivers electric current at the rated voltage as soon as operation is up to speed. These generators deliver current, U1 for charging battery SY and for energizing the various relays, signals, etc., and U2 for ener-

gizing switch motor M. Motor M now operates mechanism SM to open the switch and divert train No. 6 from the main line into the siding. As soon as the switch is opened and locked in position, the contacts 155 and 156 in the circuit of control relay C8, and 190 and 191 in the circuit of control relay C5, are closed so that both of the signals 8 and 5 will indicate "proceed," unless the block of signal 5 is occupied at some other point holding said signal at stop. When train No. 6 arrives, finding signal 8 "clear" it proceeds into the siding. Since track relays E5 and E6 control the relay H shown in Fig. 1, train No. 6 may announce its arrival on the siding to the dispatcher, similarly as heretofore described in the case of the trains operating as shown in Fig. 1. The dispatcher will now again operate the selector for commutator CM4, returning this commutator to its normal position. This causes relays SR to become de-energized, that contact 211 is made on its back point, thus causing the motor M to operate the mechanism SM to return the track switch F2 to its normal position. With track switch F2 returned to its normal position and the contacts O8 and O10 back in their normal position, signals 1 and 6 are in a condition to indicate "proceed" except as their blocks may be occupied.

Train No. 5 in the meantime approaching on the main line, finding signal 7 "clear" proceeds over the switch; but during the time that train No. 5 is on the main line between the siding switches F2 and F3, relay H being de-energized, it reports its position to the dispatcher. As train No. 6 leaves the passing siding at the other end through switch F3, operated similarly as described for switch F2, it may announce its departure to the dispatcher as heretofore explained. Also, train No. 5 may announce its departure to the dispatcher when leaving the circuit of track relay E5, for example.

After the switch F2 has been returned to its normal position, the dispatcher again operates the selective system DSE to control the commutator CM5 to return same to its normal position, thus stopping the gasoline engine GE, and, consequently, operation of the power plant.

It is assumed that the charging of the battery SY by the generator U1 will be at such a rate as to recuperate this battery for the drain upon it by the relays and signals during the interval when the power plant is not operating.

A principal feature of this invention is that of the communication zone for each train which in reality travels with the train and within the limits of which communications to and from the train are confined. Such a zone always includes a circuit, arbitrarily referred to as an intermediate circuit, in inductive relation with the train carried devices and adapted to be connected, when so desired, with communication devices in a wayside station. Such a station is more specifically referred to herein as the dispatcher's office. The operation of this traveling communication zone, or traveling intermediate circuit, will now be described.

Assume a train in the section AS, which is but partly shown in Fig. 1. The communication zone for the train is confined to the intermediate circuit for section AS. When the train, moving toward the right, enters the track circuit for relay E2, the separate identity of the intermediate circuits of section AS and section BS is temporarily destroyed in that during the interval the train is in said track circuit, these two inter-

mediate circuits are connected together in one circuit so that the limits of the communicating zone are now that of the two sections AS and BS. When the train moves from the track circuit of relay E2, the intermediate circuit for each section AS and BS is restored to its normal status. The train now being wholly within the section BS its communicating zone and intermediate circuit is that for said section. As the train proceeds into the track circuit of relay E4, the communicating zone for the train is again changed by being enlarged to cover both sections BS and CS with the intermediate circuits for each section now combined into one correspondingly large intermediate circuit comprised within the said two sections. As the train moves from the track circuit for relay E4, the intermediate circuit for each of the sections BS and CS is restored to its normal condition. The train now being within the limits of section CS its communicating zone and corresponding intermediate circuit is confined to the limits of said section. This traveling zone or circuit condition is automatically maintained by the train, similarly as described, as the train travels the length of the stretch. With this traveling zone or circuit feature, the two ends of the train or two train points, are always in uninterrupted communicative relation with each other; and with the means provided and heretofore described, both train points and the wayside station may be placed in communicative relation with each other. This novel communication zone means admits of several trains being in the stretch at one time, each within its own communicating zone, and the attendants on each train end at liberty to communicate between themselves, or to be in communication with the wayside station, without interfering with, or being interfered with by, any other train which may be within the stretch but not in the same zone.

It will be noted that, as illustrated, when two adjacent intermediate circuits are joined together into one circuit, the conductors of the two sections are connected in transposed relation; for example, with a train in the circuit of track relay E4 of Fig. 1, conductor 23 is connected to conductor 18 and conductor 20 is connected to conductor 25. The purpose of transpositions in these circuits, is to eliminate, or minimize, foreign current inductive disturbances. In certain localities, where foreign circuits, and other sources of inductive disturbances, are not present, transpositions in the intermediate circuits are not necessary. Further, where the communication impulses are by certain frequencies to which the various circuits, as necessary, are tuned, transpositions are not essential if the foreign current inductive effects are of frequencies differing from that used for communication purposes.

It will be further noted that I have not confined myself solely to the use of transpositions in intermediate circuits when, and as, adjacent intermediate circuits are joined for the interval a train is passing from one section to the section next adjoining. Figures 1 and 4 indicate transpositions of the conductors of the intermediate circuits at points between the limits of the sections. The number and style of transpositions desirable in an intermediate circuit are largely determined by conditions existing on the railroad where the installation is made. In this invention, I do not wish to be limited to the transposing of the two conductors as shown in the figures. I may alternatively make such

transpositions through transformers in a manner as illustrated in United States patent No. 1,899,105 granted February 28, 1933 to W. C. Phebus, on an application Serial No. 464,792 filed June 30, 1930. 5

There are certain advantages in the effects of induction, where it exists, from foreign electrical disturbances in intermediate circuits of the communication system described. When the dispatcher connects his receiver circuit with an intermediate circuit, the audible effect from the foreign current induced in the intermediate circuit serves as an indication that the intermediate circuit is complete and properly connected. Where such indication is desirable, this foreign current disturbance, may be used for this purpose, and thus the expense of special indication means is not necessary. 10 15

I have hereinbefore mentioned the use of radio frequencies as well as audio frequencies for conveying communications. I do not wish to be confined to the use of either or both of these. It will be observed that the system is adaptable for communication to be carried on by code, as the telegraph, by written message, as the teletype, and, in fact, by any suitable means dependent upon electrical energy. 20 25

What I claim as new is:

1. In a train communicating system, means for communicating between the head end and rear end of a train, comprising, a communicating set on each end of the train and a circuit in communicative relation with each of said communicating sets connecting between said sets, and means for communicating between either or both ends of said train and a wayside station, comprising, said first named means, a communicating set in said wayside station, and a transformer normally in disconnected relation with said circuit but adapted to be selectively connected to said circuit and said wayside communicating set for establishing communicative relations between said train ends and said wayside station. 30 35 40

2. In a system for communication between a vehicle and a wayside station, communication sets on the vehicle and in the wayside station, an intermediate circuit in electrical relation with said vehicle carried set, a wayside circuit connecting to said wayside station set, a transformer adapted for communication purposes, and means operative from the wayside station to connect said transformer in both said intermediate circuit and said wayside circuit. 45 50

3. In a system for communication between a vehicle in a stretch of track and a wayside station, communication sets on the vehicle and in the wayside station, a series of sections for said stretch each with a circuit normally in communicative relation with said vehicle carried set as the vehicle moves through the stretch, and a transformer adapted to be selectively placed in communicative relation with each of said circuits and said wayside station set. 55 60

4. In a system for providing telephonic communication between a vehicle and a wayside station, telephone sets on the vehicle and in the wayside station, means controlled by the vehicle placing said sets in communicative relation with each other, and means in close proximity to said first mentioned means and remotely controlled from the wayside station adapted to modify the vehicle control of said first named means to annul such relationship. 65 70

5. In a system for communication between a vehicle and a wayside station, communication 75

- sets on the vehicle and in the wayside station, a communication zone for the vehicle comprising a circuit within the zone to which communications to and from said vehicle are confined, and 5 means operable by the vehicle in co-operation with means within said zone controlled from the wayside station for placing said sets in communicative relation with each other via said circuit.
6. In a system for communication between a moving vehicle and a wayside station, communication sets on the vehicle and in the wayside station, a communication zone comprising an intermediate circuit traveling with said vehicle, a circuit extending from the station to said zone, and means within said zone controlled jointly 10 from said wayside station and by said vehicle for connecting said two circuits to place said sets in communicative relation with each other.
7. In a system for communication between a plurality of vehicles and a wayside station, communication sets on each vehicle and in the wayside station, a communication zone for each vehicle, and means associated with each zone, at times controlled from said wayside station and at other times controlled jointly from said wayside station and by said vehicle, adapted to place any one vehicle communication set or any several vehicle communication sets in communicative relation with said wayside station communication set.
8. In a system for communication between vehicles in a stretch of track and the wayside, sections of single track and double track in said stretch, a communication station on each of said vehicles, a communication station on the wayside, and means, adapted to place said wayside station in communicative relation with said vehicles, controlled by said vehicles as to each track of the double track sections and from the wayside station as to the single track sections.
9. In a system for communication between a vehicle in a stretch of track and a wayside station, communication sets on the vehicle and in the wayside station, a series of sections for said stretch each with an intermediate circuit in communicative relation with said vehicle carried set as the vehicle moves through the stretch, and means associated with said intermediate circuits and controlled from the wayside station through the medium of a single control circuit adapted to simultaneously place said wayside station set in communicative relation with a plurality of said intermediate circuits.
10. In a system for communication between vehicles in a stretch of track and a wayside station, a wayside assemblage comprising, a series of sections in said stretch each with an intermediate circuit, a wayside communication station, and means common to adjacent intermediate circuits and associated directly therewith operable to simultaneously place said wayside station in communicative relation with said intermediate circuits in pairs.
11. In a system for communication between the head end and rear end of a train and between either or both ends of said train and a wayside station, a transmitting set on each end of the train including an inductor in circuit with a transmitter, a receiving set on each end of the train including another inductor in circuit with a receiver, a communication transmitting and receiving set in the wayside station, and means within a communicating zone, which travels with the train, communicatively connecting said inductors and adapted to be selectively placed in communicative relation with said wayside station set.
12. In a system for communication between vehicles in a stretch of track and a wayside station, a wayside assemblage comprising, a series of sections in said stretch each with an intermediate circuit, selective means operative from and a communication circuit connected with said wayside station, a transformer having a primary coil and a plurality of secondary coils, and a relay responsive to the operation of said selective means connecting one secondary coil into one intermediate circuit, another secondary coil into another intermediate circuit and said primary coil to said communication circuit.
13. In a system for communication between a vehicle in a section of track and a wayside station, a wayside assemblage comprising, an intermediate circuit for said section, selective means operative from and a communication circuit connected with said wayside station, a transformer having a primary coil and a secondary coil, a relay responsive to the operation of said selective means having a normal position and an abnormal position, and means operative by the train while in said section effective, only when said relay is in the normal position, to connect said secondary coil into the intermediate circuit and said primary coil to said communication circuit.
14. In a system for communication between a vehicle in a stretch of track and a wayside station, communication sets on the vehicle and in the wayside station, a series of intermediate circuits for said stretch each adapted to be in communicative relation with said vehicle carried set, each of said circuits being adapted to be modified to include means for communicative relationship with said wayside station set in addition to its normal circuit elements, and means adapted to connect a plurality of said intermediate circuits together.
15. In a system for communication between the head end and the rear end of a train, a transmitting set on each end of the train including an inductor in circuit with a transmitter, a receiving set on each end of the train including another inductor in circuit with a receiver, and means operative in said receiver circuit adapted to render said receiver inactive while said transmitter is active.
16. In a train operating system under the control of a dispatcher, a stretch of railway track including a section of single track line and a section of two track line, a train in said single track section proceeding toward and into one of the tracks of said two track section, means permitting said train to pass from said single track section to said two track section, communication sets on said train and in the office of said dispatcher, means for conveying communications between said dispatcher's set and said train set, selective means in said office adapted to control both said first named means and second named means, said second named means being subject to such control only while the train is in the single track section, and means controlled by said train, controlling said second named means while the train is in the two track section.
17. In a system for communication between the head end and rear end of a train in a stretch of track and between either end or both ends of said train and a wayside station, communication sets on each end of the train and in the wayside station, means controlled by the train adapted

to place said train sets in communicative relation with each other, means in said station adapted to control said first named means to place said station set in communicative relation with either or both of said train sets for some portions of said stretch, and means controlled either by said train or by said means in said station for placing said station set in communicative relation with either or both of said train sets for other portions 5 of said stretch.

18. In a train telephone system, in combination, two intermediate circuits associated with a stretch of railroad track and adapted to co-operate with telephone apparatus carried by 15 trains occupying the track, a telephone line, a transformer comprising a primary winding and two secondary windings, and a switching device for simultaneously connecting the secondary windings in said two circuits, respectively, and 20 for connecting the primary winding to said line.

19. In a train telephone system, in combination, two closed metallic loop circuits associated with a stretch of railroad track and adapted to co-operate with telephone apparatus carried by 25 trains occupying the track, a telephone line, a transformer comprising a primary winding and two secondary windings, a switching device for simultaneously connecting the secondary windings in said two circuits, respectively, and for 30 connecting the primary winding to said line, and a second switching device for joining said two circuits to form a single closed loop circuit and for simultaneously short circuiting one of said secondary windings.

20. In a train telephone system, in combination, a stretch of railroad track, a train on said track, telephone apparatus carried by the train, a normally closed electrical circuit consisting solely of a trackway conductor co-operating with 40 the train carried telephone apparatus, a wayside conductor and switching contacts connecting said conductors together, a telephone line, a transformer having two windings, and a switching device for abnormally operating one of said 45 contacts to connect one transformer winding in said circuit and for operating another contact to connect the other transformer winding to said line.

21. In a train communication system, in combination, a stretch of railroad track, a train on said track, transmitting and receiving apparatus on the train, a closed electrical circuit comprising a trackway conductor co-operating with said transmitting and receiving apparatus, a wayside 55 conductor and switching contacts connecting said conductors together, a transformer having two windings, a communication circuit, and a switching device controlled over said last circuit for operating one of said switching contacts to 60 connect one transformer winding in said first circuit and for operating another switching contact to connect the other transformer winding to said last circuit.

22. A trackway system for conveying electrical 65 impulses between a vehicle and a wayside station comprising a first circuit associated with a stretch of track for the vehicle, a second circuit extending from the stretch of track to the station, a transformer, a relay controlled from said station 70 normally connecting one winding of said transformer in said first circuit, and a vehicle controlled relay for connecting the other winding of said transformer in said second circuit.

23. In a train communication system, in combination, a stretch of railway comprising a double

track line connecting at each end of the stretch to a single track line, a train in the stretch, a wayside station, an intermediate circuit associated with the double track line, a wayside line connecting to the wayside station, means controlled by the train on entering the stretch at either end thereof for connecting the intermediate circuit with the wayside line, and means associated with said intermediate circuit and controlled from said station for disconnecting 19 said intermediate circuit from the wayside line.

24. In a communication system for railways, in combination, a stretch of track, a plurality of intermediate circuits electrically independent of each other, said circuits each being associated with a particular portion of said stretch of track, a transformer for each intermediate circuit, a wayside station, a communication circuit associated with the stretch of track and connecting with said station, and means controlled from the 20 station over said communication circuit for connecting one winding of each of any desired number of said transformers in their associated intermediate circuits.

25. A trackway system for conveying signals to 25 and from moving vehicles comprising, in combination, a series of electrically separate intermediate circuits associated with a stretch of track for vehicles, a transformer associated with adjoining circuits of said series for inductively connecting the circuits together under certain conditions, and means associated with said adjoining circuits for conductively connecting the circuits together under other conditions.

26. In a communication system for railways, 35 a stretch of railway track with a train therein, a wayside station, an intermediate circuit for said stretch, a wayside communication circuit connected with the wayside station, means associated with said intermediate circuit and controlled by said train to connect the intermediate circuit with the communication circuit, and other means associated with said intermediate circuit controlled from said wayside station to annul said connection and thereafter to reconnect said 40 intermediate circuit with and disconnect said intermediate circuit from said communication circuit at will.

27. In a communication system for railways, a stretch of railway including a passing siding 50 location, an intermediate circuit associated with said location, intermediate circuits in said stretch adjoining on either side of said location and normally electrically isolated from the intermediate circuit at said location, a wayside communication 55 circuit, means controlled by a train for electrically connecting the intermediate circuit at said location with one of the adjoining intermediate circuits to form a single enlarged circuit, a relay controlled by the train, and contacts controlled by said relay for connecting the intermediate circuit for said location and also said enlarged circuit with said wayside communication circuit.

28. In a communication system for railways, a 65 stretch of railway including a main line track and a siding track, a switch at each end of the siding track connecting said track with the main line track, a wayside circuit associated with each of said tracks, a wayside station, a communication 70 circuit extending from said station along said tracks, means associated with the wayside circuit and controlled by a train moving over said tracks for automatically connecting the wayside circuit with the communication circuit, and 75

means associated with the wayside circuit and controlled over the communication circuit for interrupting the connection between said circuits, said connection between the circuits continuing 5 after the same has been automatically established until said last means is operated.

29. In a system for conveying electric current between a vehicle and a wayside station, an electrical transmitting and receiving circuit on the 10 vehicle and at the wayside station, a zone for the vehicle including at all times a circuit within the zone in electrical relation with the circuit on the vehicle and to which electric currents for and from said vehicle are confined, and means operable by the vehicle in cooperation with means 15 within said zone controlled from the wayside station for placing said station circuit and zone circuit in electrical relation with each other.

30. In a system of communication for railway 20 trains, a track district including a main line track and a siding track, said main line track extend-

ing away from said siding track in each direction, two trains, each on the main line track moving toward said siding, a communication set on each end of each of said trains, each set including a transmitter and a receiver and a train carried 5 circuit adapted to be connected to said transmitter and receiver, a circuit associated with said track for each of said trains in electrical relation with the train carried circuits, and a circuit associated with both said main line track and said siding track while one train is on the main line track and the other train is on the siding track 10 in electrical relation with the train carried circuits of both trains, the arrangement being such that communication may be carried on between 15 the ends of each of said trains as the trains approach the siding and between said trains while one train is on the main line track and the other train is on the siding track.
